DESIGN FOR A STOCKING

Charles W. Campbell, New York, N. Y.

Application February 13, 1937, Serial No. 67,628

Term of patent 3½ years

To all whom it may concern:

Be it known that I, Charles W. Campbell, a citizen of the United States and a resident of the Borough of Manhattan, city, county, and State of New York (post office address 31 Gramercy Park, New York city), have invented a new, original, and ornamental Design for Stockings, of which the following is a specification, reference being had to the accompanying drawing, forming part hereof, and in which Figure 1 is a side view of a stocking embodying my design and

I claim:

The ornamental design for a stocking as shown.

CHARLES W. CAMPBELL.
